UNITED STATES PATENT OFFICE

WILLIAM C. CORYELL, OF YOUNGSTOWN, OHIO, ASSIGNOR TO CENTRAL ALLOY STEEL CORPORATION, OF MASSILLON, OHIO, A CORPORATION OF NEW YORK

ROLLING MILL

Application filed April 5, 1923. Serial No. 630,121.

This invention relates to rolling mills, more particularly of the type adapted to carrying out the method of reducing metal to provide relatively thin metal strips used for making endless belts, and other purposes in the manner described in my co-pending application Serial No. 411,295 filed September 18, 1920, and my former Patent No. 1,309,244 dated July 18, 1919.

10 A primary object of the invention is to provide a rolling mill construction wherein both the reducing rollers and the main compression rolls are positively driven, thus obviating relative slippage between the rolls and 15 rollers in the reducing operation. In that connection it is pointed out that the construction and arrangement of the rollers in the present invention are more especially adapted to producing a continuous strip which may 20 be made into the form of a belt by welding or otherwise as shown in my co-pending application above referred to.

25 A further object of the invention is to provide a novel arrangement of reducing rolls and main compression rolls, the latter having a special non-frictional mounting which materially reduces the amount of power required for driving and contributes generally to the efficiency of the mill.

30 With the above and other objects in view which will more readily appear as the nature of the invention is better understood, the same consists in the general construction, combination, and arrangement of parts, hereinafter more fully described, illustrated and claimed.

A preferred and practical arrangement is shown in the accompanying drawing, in which:—

40 Figure 1 is a vertical cross-sectional view taken at right angles to the axis of the rolls.

Figure 2 is a vertical cross-sectional view.

Similar reference characters designate corresponding parts throughout the several 45 figures of the drawings.

As previously indicated the present mill is particularly adapted for the production of thin metal strips which are made by rolling or pressing the rough stock preliminarily 50 while the same is hot, the finishing work be-

ing performed while the metal is at a lower temperature, or when it is cold.

Referring more particularly to the drawings it will be observed that the main compression rolls A and B are mounted in a 55 suitable frame C so as to be relatively adjustable, as for example in the general manner proposed in my Patent No. 1,221,029 dated April 3, 1917, and have arranged therebetween the reducing rolls A' and B'. These 60 rolls are carried in the same blocks as the main rolls and are adjustable therewith to provide the desired pass for the metal bar M according to the amount of squeezing or reducing required.

65 The main compression rolls A and B each preferably consist of a shell or hollow cylinder 1 mounted upon a bearing member or mandrel 2 by the anti-friction bearing elements 3 which may be roller bearings of conventional form. Thus, the shell 1 of each of the main compression rolls is mounted to be freely rotatable upon a bearing member or mandrel, and at one end of each shell there is formed a gear ring 4 while at the opposite 70 end there is provided another gear ring 5. The latter gear ring of each compression roll unit is adapted to mesh with a gear ring 6 provided at the end of one of the reducing rolls, thereby positively driving both 75 of said rolls from the main compression rolls.

80 As will be observed from Figure 2 the shells 1 of the main compression rolls A and B are coextensive in length with the reducing rolls A' and B' so that the full compressive 85 force of the compression rolls are transmitted to the reducing rolls.

85 From Figure 1 it will be observed that the shells 1 of the main compression rolls A and B are driven by the gears 7 which engage 90 with the gear rings 4 of the shells. Therefore, each of the main compression roll units A and B is positively driven and in turn each shell positively drives its reducing roll. By 95 this arrangement the rolls A' and B' are interlocked positively with the shells of the main rolls so that there is no chance of the metal M passing between the rolls A' and B' except as it may be definitely fed through 100

and between the rolls by the rotation of the main compression rolls.

5 A pulling device P is associated with the metal strip C and exerts a stretching or pulling force on the strips simultaneously with the compressive force exerted by the rolls and reducing rolls.

10 Since the rolls A' and B' are positively interlocked with the main driving rolls A and B the tension imposed on the strip S will not cause the rolls to slip, thereby insuring that all of the metal is subjected to the desired squeezing.

15 In connection with the shells 1 of the main compression roll units A and B it is pointed out that the gear rings 4 thereof will always mesh with the driving gear 7 without disturbing the proper gear relation therebetween. That is to say the axis of the driving gears 7 lies in a vertical plane at one side of the vertical plane intersecting the axes of the roll units A and B, and therefore in a horizontal plane at right angles to the said vertical plane intersecting the roll 20 axes, thus permitting vertical roll adjustment or movement without affecting the proper relation of the gears.

25 From the foregoing it is believed that it will be clear that the arrangement proposed 30 provides a construction wherein the reducing rolls A' and B' are positively interlocked with the main compression rolls A and B thereby preventing relative slippage of the rolls A' and B' under the tension of the pulling 35 device, and compelling all of the fibres of the metal to be properly compressed and definitely fed between the rolls A' and B' at the desired speed. In this way treatment 40 of the metal is fully controlled and a uniform product is insured.

45 Without further description it is thought that the features and advantages of the invention will be readily apparent to those skilled in the art, and it will of course be understood that changes in the form, proportion 50 and minor details of construction may be resorted to without departing from the spirit of the invention or scope of the appended claims.

55 I claim:—

1. A rolling mill including a pair of relatively adjustable main compression rolls, each roll including a stationary supporting member, a cylindrical shell, a gear ring provided 60 at one end of the shell, a driving gear engaging with said gear ring, a gear ring at the opposite end of the shell, reducing rolls in contact with the periphery of the shell, and a gear at one end of each reducing roller for engaging one of the gears on a shell.

65 2. A rolling mill comprising a pair of relatively vertical adjustable main compression rolls, each provided with gear rings at its opposite ends, a driving gear meshing with the gear ring at one end of each roll and dis-

posed at one side thereof in a horizontal plane at right angles to the vertical plane intersecting the axis of the roll and a reducing roll having a gear engaging the other gear ring of each roll.

70 In testimony whereof I hereunto affix my signature.

75 WILLIAM C. CORYELL.
